UNITED STATES PATENT OFFICE.

WILLIAM C. ANDERSON, OF TOLEDO, OHIO.

DESIGN FOR A GLASS DISH.

SPECIFICATION forming part of Design No. 24,874, dated November 12, 1895.

Application filed July 21, 1894. Serial No. 518,275. Term of patent 7 years.

To all whom it may concern:

Be it known that I, WILLIAM C. ANDERSON, of Toledo, county of Lucas, and State of Ohio, have invented a certain new and original Design for Dishes; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to a design for dishes, and pertains to the exterior surface ornamentation thereof.

Figure 1 is a plan view of the dish embellished with my design. Fig. 2 is a sectional elevation on line $x-x$, Fig. 1.

The center of the dish or flattened portion forming the bottom of the same has an ornamentation comprising lines forming a many-pointed star 1, and a central stud. At a point midway of the points of the central star-shaped figure and extending to near the upper edge of the dish are curved lines, which form three encircling rows, respectively, of kite-shaped figures 2, 3, and 4, each alternate figure 2 being embellished with intersecting cross-hatching, the remaining figures being divided by intersecting lines into frusto-pyramidal-shaped projections and prisms. Kite-shaped figures 3 are divided by intersecting lines into four parts, one of which is a frusto-pyramidal-shaped projection having an or-

namentation upon the top thereof, the three remaining sections being divided by intersecting lines into prisms. Figures 4 are embellished, each alternate figure being formed by intersecting lines into a series of frusto-pyramidal projections, the top of each projection being crossed by intersecting lines, the opposite sections 4 being by intersecting lines divided into four portions, the lower portion being embellished by intersecting lines, the upper portion by intersecting cross-hatching, each side portion being divided by intersecting lines into prisms and projections, the top of the projections being embellished by intersecting cross-hatching. Between the upper portions of the upper row of figures 4 is an outer row of prisms 5 in fan shape, each prism radiating to a common center.

The leading features of my design consist in the central many-pointed star, the three encircling rows of kite-shaped figures with intermediate patterns, and the outer row of fan-shaped prisms, intersected and embellished as shown.

What I claim is—

The design for a dish, as herein shown and described.

In testimony that I claim the foregoing as my own I hereby affix my signature in presence of two witnesses.

WILLIAM C. ANDERSON.
